UNITED STATES PATENT OFFICE.

ARTHUR GIESLER, OF DAYTON, OHIO, ASSIGNOR TO THE STILWELL-BIERCE & SMITH-VAILE CO., OF DAYTON, OHIO, A CORPORATION OF NEW JERSEY.

HORIZONTAL-WATER-WHEEL SYSTEM.

SPECIFICATION forming part of Letters Patent No. 705,993, dated July 29, 1902.

Application filed October 1, 1900. Serial No. 31,689. (No model.)

To all whom it may concern:

Be it known that I, ARTHUR GIESLER, a citizen of the United States, residing at Dayton, in the county of Montgomery and State 5 of Ohio, have invented certain new and useful Improvements in Horizontal-Water-Wheel Systems; and I do declare the following to be a full, clear, and exact description of the invention, such as will enable others skilled 10 in the art to which it appertains to make and use the same, reference being had to the accompanying drawings, and to the letters of reference marked thereon, which form a part of this specification.

15 This invention relates to improvements in water-wheel systems and possesses the new and useful features hereinafter described and claimed.

In my pending application, filed September 27, 1900, Serial No. 31,243, I show an air-valve operated by means of a water-float and adapted to discharge air into the upper portion of the turbine-casing by means of a passage leading from said valve to said turbine-casing. In the present invention I employ 25 an automatic air-valve, which is operated by atmospheric pressure to admit air directly to the turbine-casing, the said valve being mounted on the wheel-casing.

30 Experience in connection with the manufacture and installation of turbine water-wheels has demonstrated that in very many instances, owing to the physical conditions, it is desirable and necessary to place said 35 turbine water-wheels a considerable distance above the water in the tail-race. In order to do this without loss of head and subsequent loss of power, it becomes necessary to connect the turbine wheel with the water in the tail-race by means of a draft-tube which may be 40 varied in length according to requirements. With certain types of water-wheels—to wit, those known as the "impulse" or "Girard" type—my experience has demonstrated the 45 desirability of maintaining the height of the water in the draft-tube at a predetermined level and that this can be best accomplished by the admission of air to the wheel-casing or draft-tube above the level. The quantity

of air required for this purpose depends upon 50 the quantity of water the wheel is discharging, which will depend upon the stage of opening of the water-wheel gate, which in turn depends upon the load the water-wheel is carrying—*i.e.*, in practice the water-wheel 55 gate is controlled by a governor or regulator, which opens or closes it to accommodate the varying load on the wheel. The height of water in the draft-tube having been determined at a point where the water-wheel will 60 develop its greatest efficiency, it is evident that a device for maintaining that level under varying loads becomes a great desideratum. The result is accomplished by my invention, which I will now describe.

In the drawings, Figure 1 represents a sectional elevation of a water-wheel system constructed in accordance with my invention. Fig. 2 is a detail of the locking-bar for the valve-lever.

In the specification similar letters of reference indicate corresponding parts.

A designates a turbine-wheel casing, which is suitably mounted above the tail-race and is connected with said tail-race by a draft-tube B, the said draft-tube being of requisite length to extend from the tail-race to the casing. On the interior of the casing there are arranged two deflector-plates L, extending throughout the length of the casing and 75 inclining inwardly. These plates provide a suitable compartment, into which the air is discharged. Within this casing there is mounted horizontally one or more turbine wheels C on shaft C' in the usual manner, 80 said turbine wheel or wheels being of the impulse or Girard type. The upper portion of the casing is provided with a nozzle D, upon which is mounted an automatic or non-automatic air-valve E, which opens into the casing. Through this valve atmospheric pressure is admitted to the casing to maintain the water at a predetermined level. The said air-valve may be placed at any point between the upper portion of the wheel-casing and the 90 tail-water and the same results obtained. The valve seats against an elbow or pipe F, which connects with the nozzle D and opens

to the atmosphere. The valve-stem E' is inclosed by a helical spring E'', which maintains it normally against the valve-seat. The spring is inclosed in a housing or extension H.

- 5 I designates a lever which is fulcrumed at at I' and is connected to the valve-stem E'. The lever I is provided with a weight J, which may be placed at various points along said lever to vary the weight thereon.
- 10 When the atmospheric pressure exceeds the pressure within the wheel-casing or the draft-tube, which condition takes place whenever a vacuum or partial vacuum occurs within the wheel-casing or draft-tube, the atmospheric pressure unseats the valve E, and such pressure is then admitted to the casing. In other words, whenever the rarefied condition within the wheel-casing plus the weight on the valve-lever and the atmospheric pressure 15 on the outside of the wheel-casing are not in balance atmospheric pressure acting against the said weight will open the said valve and admit air. This condition takes place when the water within the wheel-casing rises 20 above the predetermined level. Atmospheric pressure entering the wheel-casing through said valve will exert the necessary pressure upon the surface of the water within said casing to maintain the desired water-level.
- 25 The wheel-casing is exhausted of air by the water entering the said casing through radial discharging turbine wheel or wheels. The air is exhausted or rarefied to an extent that is due to the height from the tail-water to 30 the predetermined level of water within the turbine-casing. For example, the distance between the predetermined point of the tail-water is, say, ten feet. It follows, therefore, that a correct vacuum-gage would register

about nine inches of vacuum. The air-valve 40 E may be operated automatically to admit atmospheric pressure to the turbine-casing, or it may be opened and maintained in an open position manually by the following devices:

45 K designates a bar which is rigidly mounted in proximity to the valve E. This bar has a longitudinal opening K', in which the lever I projects and is movable to various positions. The bar K has also a series of openings K'', 50 through which a pin K''' may be inserted below the lever I to support said lever in any desired position, depending upon the valve-opening.

55 I do not wish to limit myself to the identical form of valve shown, as other forms of valves operated automatically or manually will perform the same service.

Having described my invention, I claim—

60 In a water-wheel system, the combination of a turbine-casing, a draft-tube connecting said casing with the tail-water, a turbine in said casing, said turbine being of the impulse or Girard type, an air-valve opening into said casing above the surface of the water and 65 upon the discharge side of the turbine, and yielding means to resist the opening of said valve by the atmosphere, whereby the height of the tail-water may be maintained approximately at a constant level for the purpose set 70 forth.

In testimony whereof I affix my signature in presence of two witnesses.

ARTHUR GIESLER.
